UNITED STATES PATENT OFFICE.

LOUIS DE PLANQUE, OF JERSEY CITY, NEW JERSEY.

DESIGN FOR A PANEL.

SPECIFICATION forming part of Design No. 14,417, dated November 13, 1883.

Application filed September 12, 1883. Term of patent 3½ years.

To all whom it may concern:

Be it known that I, LOUIS DE PLANQUE, of Jersey City, in the county of Hudson and State of New Jersey, have invented and produced a new Design for Panels, of which the following is a full, clear, and exact description.

The object I desire to accomplish is to provide a new design for panels for receiving paintings, sketches, pictures, &c.

Reference is to be had to the accompanying drawings, forming a part of this specification, in which similar letters of reference indicate corresponding parts in all the figures.

Figure 1 is a face view of my newly-designed panel. Fig. 2 is a cross-sectional view of the same. Fig. 3 is a longitudinal sectional view of the same. Fig. 4 is a diagonal sectional view of the same.

The panel A, which may be square or oblong, is made concave, so that any section-line will be a concave curve.

The above-described panel is to receive paintings, sketches, pictures, designs, and photographs; or leaves, flowers, or paper figures can be pasted on the same; or it can be ornamented in any other suitable style in the same manner that plaques and flat panels are ornamented.

Having thus described my invention, I claim as new and desire to secure by Letters Patent—

The herein-described design for a panel, having angular corners and a concave face, as set forth.

LOUIS DE PLANQUE.
